Patented Aug. 28, 1917.

UNITED STATES PATENT OFFICE.

FRANK W. WOLFF, OF PARNASSUS, PENNSYLVANIA, ASSIGNOR TO P. H. MURPHY COMPANY, OF PARNASSUS, PENNSYLVANIA, A CORPORATION OF PENNSYLVANIA.

CARLINE.

1,238,470.

Specification of Letters Patent. Patented Aug. 28, 1917.

Application filed January 16, 1917. Serial No. 142,584.

To all whom it may concern:

Be it known that I, FRANK W. WOLFF, a citizen of the United States, and a resident of Parnassus, Pennsylvania, have invented a new and useful Improvement in Carlines, of which the following is a specification.

This invention relates to forged steel carlines for freight cars, and particularly to carlines made from commercial shapes such as I-bars, channels and Z-bars. The objects of the invention are to produce a light, strong, inexpensive carline, which will take up little head room in the car and which 15 does not require the side plates to be deeply notched where its ends are secured to them.

Further objects and details of the invention appear in the following description of the several carlines shown in the accompanying drawings. What is claimed as the 20 invention appears from the appended claims.

In the drawings, wherein the same reference characters are used to designate the same or similar parts in the several views,

25 Figure 1 is a plan view of a portion of a carline of I-section embodying the invention;

Fig. 2 is a side elevation of the same; and Figs. 3 and 4 are cross-sections of the carlines shown in Figs. 1 and 2, taken on the 30 lines 3—3 and 4—4, respectively, in Fig. 6, looking in the directions indicated.

Figs. 5 and 6 are a plan view and a side elevation, respectively, of the end portion 35 of a modification of the invention comprising a separately formed end saddle or gusset plate which is riveted to the end of the carline; and

Fig. 7 is an end view of the same. 40 The carline 27 shown in Figs. 1 to 4 comprises an I-beam arranged with its web 33 vertical, and bent downward on each side of the middle to conform to the pitch of the car roof. The top flange 28 has portions 45 of its edges bent up alongside of the seats for the ridge pole and purlins to position these members where they belong. The lower flange 30 is continuous from end to end and is bent down at the ends to form 50 lugs 31 for bolting to the inside faces of the side plates. The top flange extends beyond the lateral lugs 34 at the ends of the web over the side plate and is bent down against the outer side of the side plate to form a 55 lug 32 for securing the carline to the side

plate. The end portion of the web is split in lengthwise halfway between the top and bottom flanges about as far as the seat for the outside purlin, and the two split portions of the web are lapped for their full width 60 at the ends of the carline, and are securely riveted together. This arrangement causes the top and bottom flanges to converge toward the ends of the carline, and diminishes the height of the carline at the eaves. The 65 split ends of the web 33 are severed close alongside of the flanges for a few inches in from each end, and the severed portions are bent sidewise on each side of the web to form lateral lugs 34 for bolting against the 70 inside faces of the side plates.

The carline 39 shown in Figs. 5, 6 and 7 is an I-section carline having its ends cut off square, the web being split horizontally, as in the carline 27. Separate end bracket 75 members 40, each of which has a flanged stem portion 41, are arranged one on each side of the web of the carline, and are securely riveted to each end of the carline 39 by the same rivets which connect the ends of 80 the split web. The brackets rest upon the side plates, and have sufficient width to provide a good bearing thereon to resist any tendency of the carline to tip or twist with respect to the side plates, whereby the 85 carline braces the two side plates against movement caused by distortion of the car frame. Each bracket has an inner flange 41 bent down to engage against the inner face of the side plate, and an outer flange 43 bent 90 over the outer face of the side plate, forming a very rigid connection between the carline and side plate when the parts are bolted together.

It is evident that further modifications of 95 the invention can be made, and the invention is not restricted to either of the forms shown.

I claim as my invention:

1. A carline comprising a main member 100 having top and bottom flanges, and a web disposed vertically, the ends of said web being split lengthwise and the split portions lapped and riveted together at their ends whereby said flanges converge toward 105 the ends of the carline, the ends of said split portions having oppositely extending vertically co-extensive lateral projections adapted to be secured to the side plates.

2. In combination with a car, a carline 110

comprising a main member having top and bottom flanges, and a web disposed vertically, said web terminating at the inner sides of the side plates, the ends of said web being split lengthwise and the split portions lapped and riveted together at their ends by horizontal rivets whereby said flanges converge toward the ends of the car-

line, and extension portions secured by said rivets to the lapped ends of said webs and projecting over the side plates in line with said top flanges to support said carlines from the side plates. ¹⁰

Signed at New Kensington, Pa., this 8th day of January, 1917.

FRANK W. WOLFF.
